UNITED STATES PATENT OFFICE

CLARENCE W. STEMEN, OF LIMA, OHIO

AUTOMATIC SIGNAL

Application filed May 8, 1931. Serial No. 536,005.

This invention relates to automatic signalling devices and has for an object to provide a device for automatically blowing the whistle of a steam or electric train as it approaches a crossing.

A further object is to provide mechanism operatively connected to the whistle and motor driven to produce a predetermined signal when the motor circuit is closed by a switch, one member of which is located on one of the cross ties, and the other member of which is preferably mounted on the frame of the locomotive or other part of the train.

A still further object is to provide a relay for maintaining the device energized to produce the desired signal after the circuit has been momentarily closed by the train passing over the track switch member.

A still further object is to provide a circuit breaker operated by a pin on the whistle-blowing cam for de-energizing the device, the momentum of the motor carrying the pin past the circuit breaker to reset the circuit breaker for the next operation.

A still further object is to provide an operative connection between the device and valve of the whistle which will permit of the whistle being blown by hand when desired without interfering with the automatic operation of the device, so that emergency signals may be blown as frequently as necessary.

A still further object is to provide an extremely strong and durable device which will be weather-proof and dust-proof and may be placed in any convenient location on the car or locomotive and will take its current from the usual lighting generator of the train.

With the above and other objects in view the invention consists in certain novel details of construction and combinations of parts hereinafter fully described and claimed, it being understood that various modifications may be resorted to within the scope of the appended claims without departing from the spirit or sacrificing any of the advantages of the invention.

In the accompanying drawings forming part of this specification,

Figure 1 is a side elevation of a locomotive

equipped with my improved automatic whistle blower,

Fig. 2 is a longitudinal sectional view through the apparatus, with the whistle shown in elevation,

55

Fig. 3 is a cross sectional view through the apparatus, showing the parts in plan,

Fig. 4 is a vertical sectional view taken on the line 4—4 of Fig. 2,

Fig. 5 is an enlarged longitudinal sectional view, with parts in elevation, showing the track member and car member of the switch in contact,

60

Fig. 6 is a vertical sectional view taken on the line 6—6 of Fig. 5,

65

Fig. 7 is a diagrammatic view showing the electric circuits, and

Fig. 8 is a detail view showing a modified form of drive for the cam.

Referring now to the drawings in which like characters of reference designate similar parts in the various views, the whistle-blowing device is shown, for the purpose of illustration, as being applied to a locomotive

70

Referring more especially to Figs. 5 and 6, it will be seen that a block 11 of wood or other desired insulating or other material, hereinafter termed a shunt block, is lagged to a cross tie 12 near the approach to a crossing. The top surface of the block is arched and projects about an inch more or less above the adjacent rail 13. Countersunk openings are formed in the block to receive the lag screws 14. A metal contact plate 15, formed of copper or other material, is shaped to fit the top of the block and is firmly attached thereto by bolts, screws or other similar connections. This block, with its metal cover, forms one member of a switch.

75

The other member of the switch is formed by a pair of laminated brushes 16 which are secured to a block 17 of insulating material which may be bolted, as shown at 18, or otherwise rigidly secured to the frame 19 of the locomotive or other convenient part of the train so that the brushes 16 will have wiping contact with the contact plate 15 of the shunt block as the train passes thereover. The brushes momentarily close an electric circuit,

80

85

90

95

100

hereinafter described, and are, of course, of spring material so as to make positive frictional contact with the plate 15 while the brushes are wiping over the plate.

5 By referring more particularly to Figs. 1 and 2, it will be seen that the whistle 20 is provided with the usual bell crank lever 21 which may be operated by the usual cord 22 to open the valve 23 and blow the whistle by hand when desired. In applying the invention, a link 24 is pivoted at the lower end, as shown at 25, to a bracket 26 which preferably is clamped to the steam pipe 27, and the upper end of which is inserted between the lower end of the bell crank lever and the valve stem 23. A push rod 25 is connected to the link by means of a clevis 26 and pin 27, and when the push rod is moved forwardly, as will be hereinafter described in detail, the 20 whistle may be blown automatically without interfering with the manual operation of the cord-operated crank 21 to blow the whistle manually when desired.

Referring now more particularly to Figs. 25 2, 3 and 4, it will be seen that the push rod 25 passes through a stuffing box 28 in the end wall of a casing 29 which may be disposed in the cab or on the boiler or at other desired location. Disposed within the casing so as to be protected from the weather and dust, there is a motor 30 which may be operated from the lighting or other electric circuit of the train and which is controlled by a relay operated initially by the track 35 switch and as will hereinafter be more fully explained. The motor is geared to a cam shaft 31 by means of a suitable gear train comprising gears 32, 33 and 34 and pinions 35, 36 and 37 suitably mounted on shafts 38, 40 39 and 40 journaled on pointed screws, designated in general by the numeral 41, said screws being carried by a frame 42 and held in adjusted position by jamb nuts 43.

However, the gear train may be eliminated 45 if desired, and, as shown in Fig. 8, a worm 44 may be mounted on the motor shaft 45 to mesh with a gear 46 keyed to the cam shaft 47. Other operative connections between the motor shaft and cam shaft may be utilized 50 in lieu of either of the mechanisms described.

A cam 48 of any suitable material is fixed to the cam shaft and is of suitable configurations to produce any desired combination of long and short blasts of the whistle, as will 55 presently appear. A substantially right angular rocker arm 49 is pivoted at the elbow, as shown at 50, on the frame 42, and one end of the arm is equipped with a roller 51 which rides on the periphery of the cam. The opposite end of the rocker arm is slotted, as shown at 52, to receive a clevis pin 53 carried by a clevis 54 secured to the inner end of the above-mentioned push rod 25. It is now clear that when the cam is rotated through a 60 complete revolution, the raised portions of

the cam will elevate the roller 51 and push the push rod 25 to produce a blast from the whistle, the spring 55 of the whistle valve stem returning the push rod to cause the roller to follow the contour of the cam in the usual manner.

70 The relay for controlling the motor will now be described. As shown best in Figs. 2, 3 and 4, the relay is housed in a suitable dust-proof and weather-proof casing 56 removably secured to the rear end wall of the first-mentioned casing 29 by means of screws 57 or otherwise. The relay core 58 is preferably of F shape and is mounted on a suitable block 59 of insulation, and carries the usual coil 60. The relay armature 61 bridges both branches of the F-shaped core, as best shown in Fig. 2, and is mounted on the upper end of the arm 62, the lower end of the latter being fixed to a rock shaft 63. A bracket 64, best shown in Fig. 2, limits movement of the armature away from the core, and, preferably, the armature is loosely mounted on the arm 62 by means of a pin 65 which passes through the arm, a spring 66 being mounted on the pin and held under any desired tension by a nut 67.

90 The above mentioned rock shaft 63 is journaled at the ends on pointed screws 68 carried by brackets 69, jamb nuts 70 being provided on the screws to permit of suitable endwise adjustment of the rock shaft.

95 Disposed on the rock shaft is a spring contact 71 the purpose of which is to hold the relay energized after the circuit is momentarily made by the train passing over the track switch, as will hereinafter be more fully described, and also disposed on the rock shaft is a pair of spring contacts 72 each of which is connected at one end with a corresponding terminal 73 connected in circuit with the motor. The free ends of the contacts 72 engage corresponding contacts 74, disposed on the insulation block 59, when the rock shaft is rocked inwardly by energizing 100 of the relay, and these contacts are connected in circuit with the main current supply, such as the train supply generator, as indicated diagrammatically in Fig. 7.

110 In wiring the apparatus, it will be seen that a contact 75 disposed on the insulation block 59 is connected in circuit by conductor wires 76 and 77 with the generator and with one of the spring arms 16 forming the movable member of the track switch and carried by the frame of the locomotive. The other spring arm 16 of said switch is connected by a conductor wire 78 with one terminal of the relay coil. The other terminal of the relay coil is connected by a conductor wire 79 with the movable arm 80 of a circuit breaker, which will be hereinafter fully described, the fixed arm 81 of which is connected by a conductor wire 82 in circuit with the generator, as shown.

Thus, briefly, it will be seen that when the train passes over the shunt block, the contact arms 16 will be bridged by the metal plate 15 on the shunt block, thereby closing the circuit at this point from the generator through the conductor wires 76, 77, and conductor wire 78, to the relay coil, and from thence to the conductor wire 79 through the closed arms 80 and 81 of the circuit breaker, and from thence to the conductor wire 82 to the generator, whereby the relay coil is energized and the armature 61 is attracted, with resultant rocking of the shaft 63 to rotate the contacts 72 into engagement with the contacts 74. The current then also flows from the generator through these contacts and through the terminals 73 to the motor, energizing the motor, with resultant rotation of the cam 48 to blow the whistle.

Again referring to Fig. 7, it will be observed that a conduit wire 83 connects the above mentioned contact 71 with the lead wire 78 of the relay coil. When the circuit is momentarily closed at the track switch to energize the relay coil, the contact 71 carried by the rock shaft 63 will be rocked into engagement with the above-mentioned contact 75 due to movement of the armature communicated to the rock shaft 63, and will maintain the relay coil energized, by short circuiting the relay circuit through the lead wire 78, after said circuit has been opened at the track switch by the train passing beyond the shunt block. Energizing of the relay coil will thus be continued, while, simultaneously, the circuit from the generator to the motor is maintained closed by the rock shaft holding the contacts 72 in engagement with the contacts 74.

When the cam has made one complete revolution, the arm 80 of the circuit breaker is struck by a laterally disposed pin 84 carried by the cam, as best shown in Fig. 2, whereupon the arm is raised and the circuit broken at the contact points 85 of the circuit breaker. The circuit breaker is connected in series with the relay coil, as above explained. When the circuit breaker is opened by the pin, the relay coil will be de-energized, allowing the armature to drop back until stopped by the stop arm 64. While gravitating the armature rotates the rock shaft in a retrograde direction to disengage the contacts 72 from the contacts 74 in the motor circuit and open the motor circuit so that the motor also is de-energized.

The circuit breaker, consisting of the horizontal spring arms 80 and 81 separated by a block 86 of insulating material, is secured to a bracket 87, as best shown in Fig. 2, carried by the frame 42, and overhangs the cam. Thus the movable arm 80 is struck by the pin 84 just as the pin is passing over top center. The momentum of the motor carries the pin 84 onwardly, thus permitting the spring arm

80 to drop after the pin passes therebeyond, and close the contacts 85 to set the circuit breaker for the next operation.

If desired, a switch 88 of the push button type may be connected across the leads 77 and 78 of the switch arms 16 to close the circuit from the main source of supply through the relay and produce the above cycle of operations whenever it is desired to electrically blow the whistle for emergency signals.

For controlling the speed of the motor, a rheostat 89 is mounted in the end wall of the casing 29 and is connected in the motor circuit as desired. Additional adjustment of the motor speed may be made by other resistances located in the field of the motor if desired, it being merely beneficial that some means of motor speed control be utilized to control the speed of the cam 48.

From the above description, it is thought that the construction and operation of my invention will be fully understood without further explanation.

Having thus described the invention, I claim:

1. The combination with a train whistle, of a motor, a cam driven thereby and operatively connected to the whistle for blowing the whistle, a generator, a switch having coacting members carried by the train and track, a relay electrically connected in circuit with the switch and with the motor and generator and adapted to close the motor circuit upon closing of said switch, means operated by the relay to maintain the relay energized after the switch is opened, and means operated by the cam to de-energize the relay and simultaneously open the motor circuit at a predetermined point in the rotation of the cam.

2. The combination with a train whistle, of a motor, a cam driven thereby and operatively connected to the whistle for blowing the whistle, a generator, a switch having coacting members carried by the train and by the track, a relay electrically connected in circuit with the switch and with the motor and generator and adapted to close the motor circuit upon closing of said switch, a contact for short circuiting the relay circuit to said switch and moved by the relay to maintain the relay circuit closed after opening of said switch, and a circuit breaker opened by the cam at a point in its travel to open the relay and motor circuit.

3. The combination with a train whistle, of a motor, a generator, a cam geared to the motor and operatively connected to the whistle for blowing the whistle, a switch having coacting members carried by the train and track, a relay connected in circuit with the switch and with the motor and the generator and adapted to be energized by closing of the switch, a rock shaft movable as a

unit with the armature of the relay, contacts carried by the shaft for closing the motor circuit when the relay is energized, an additional contact carried by the shaft for short circuiting said switch and maintaining the relay energized after said switch is opened, and a circuit breaker operated by the cam to de-energize the relay at a predetermined point in the rotation of the cam.

4. The combination with a train whistle, of a pivoted lever on the whistle for opening the valve of the whistle, a push rod connected to the lever for moving the lever, a casing, a motor housed in the casing, a cam operatively connected to the motor to be driven thereby, a pivoted angular lever connected to the push rod and having a roller riding on the periphery of the cam, a switch having coacting members carried by the train and track, a generator, a relay electrically connected in circuit with the switch and with the motor and the generator and adapted to close the motor circuit upon closing of said switch, means operated by the relay to maintain the relay energized after the switch is opened, and means operated by the cam to de-energize the relay and simultaneously open the motor circuit at a predetermined point in the rotation of the cam.

5. The combination with a train whistle, of a motor, a cam driven thereby and operatively connected to the whistle for blowing the whistle, a generator, a switch having coacting members carried by the train and track, a relay electrically connected in circuit with the switch and with the motor and generator and adapted to close the motor circuit upon closing of said switch, means operated by the relay to maintain the relay energized after the switch is opened, a laterally disposed pin on the cam, and a circuit breaker overhanging the cam and disposed in the path of the pin to be opened by the pin at a point in its travel, said circuit breaker being electrically connected in series with the relay for de-energizing the relay to open the motor circuit when the pin impinges against the circuit breaker.

6. The combination with a train whistle, of a motor, a cam driven thereby and operatively connected to the whistle for blowing the whistle, a generator, a switch having coacting members carried by the train and track, a relay electrically connected in circuit with the switch and with the motor and generator and adapted to close the motor circuit upon closing of said switch, a contact moved by the relay armature for short circuiting the switch to maintain the relay energized after opening of said switch, a lateral pin carried by the cam, and a circuit breaker in the path of movement of the pin adapted to be opened by the pin to open the relay circuit and deenergize the relay, said circuit breaker being positioned to be struck

by the pin at top center so that the momentum of the motor carries the pin past the circuit breaker to permit the circuit breaker automatically closing after the pin passes therebeyond.

7. The combination with a train whistle, of a motor, a cam driven thereby and operatively connected to the whistle, a generator, a shunt block adapted to be secured to one of the cross ties of the track, a metal contact plate secured to the top of the block and forming one member of a switch, a pair of brushes insulated from each other and adapted to be secured to the train to have wiping contact with said plate and forming the other member of said switch, a relay electrically connected in circuit with said brushes and with the motor and generator and adapted to close the motor circuit upon contact of said brushes with said plate, means operated by the relay to maintain the relay energized after said brushes progress beyond said plate, and means operated by the cam to de-energize the relay and simultaneously open the motor circuit at a predetermined point in the rotation of the cam.

In testimony whereof I affix my signature.
